Patented Sept. 28, 1920.

UNITED STATES PATENT OFFICE.

ALFRED C. DE LORME, OF EAST ORANGE, NEW JERSEY, ASSIGNOR TO SPLITDORF ELECTRICAL COMPANY, OF NEWARK, NEW JERSEY.

IGNITION SYSTEM.

1,353,990.

Specification of Letters Patent. Patented Sept. 28, 1920.

Application filed December 31, 1918. Serial No. 269,088.

To all whom it may concern:

Be it known that I, ALFRED C. DE LORME, a citizen of the United States, residing at East Orange, in the county of Essex and State of New Jersey, have invented certain new and useful Improvements in Ignition Systems, of which the following is a specification.

This invention relates to an ignition system for use in connection with internal combustion engines, and more particularly to large multi-cylinder engines, such as used on airplanes, which are hard and in many cases dangerous in starting. In the latter class of engines it is customary to provide two ignition devices, preferably in the shape of magnetos, one of which is directly connected with the engine to furnish the ignition current after the engine has been started and another ignition machine, which can be operated by hand independently of the engine, for furnishing starting current.

In starting airplane engines with this type of an ignition system installed thereon, it is the usual practice to prime the engine cylinders by the injection of liquid fuel or by turning the engine over through the medium of the propeller, the ignition being switched to the "off" position while the engine is being turned. The act of turning the engine over by the propeller draws in charges of fuel into the cylinders and there will be at least one such cylinder in which the piston has passed over "dead center" and is in what is known as the working stroke. It is the function of the starting magneto then to furnish current to the spark plug of the cylinder in which the piston is in the working stroke. The charge in this cylinder being under a certain amount of compression will be ignited and the explosion will turn the engine over sufficiently for the service magneto, which is connected to a spark plug in the cylinder in which the piston is on the compression stroke or in advance of the one that is in the working stroke, to pick up the engine after which the operation of the starting magneto is discontinued. One method of operating such an ignition system is described in a patent to G. Honold *et al.*, #1,014,824, issued January 16, 1912.

It is the object of my present invention to provide improvements in certain details which will add to the efficiency of such system.

In the drawing Figure 1 is an end view of a distributor block used in the system.

Fig. 2 is a sectional view on the line 2—2 of Fig. 1.

Fig. 3 is a view similar to Fig. 2 but for 60 a block used with an ignition machine having a direction of rotation opposite that using the block for Fig. 2.

Fig. 4 is a plan view of the distributing member operating within the distributor 65 block.

Fig. 5 is a right hand end view of Fig. 4.

Fig. 6 is a part longitudinal and sectional view of Fig. 4 showing diagrammatically 70 the electrical connections of the starting and running ignition devices to the distributing member.

Referring now to the details, wherein like numbers refer to corresponding parts in the various views, 1 is a distributor block which 75 is adapted for use in connection with an eight cylinder engine. The distributor contacts are arranged in two rows A and B, there being eight contacts in each row. The contacts in the row toward the front of the 80 block have connectors 2 adapted to be connected to the spark plugs 3 to 10 inclusive which it is understood are located in the engine cylinders. A distributing member 11, which is operatively driven by the engine, preferably through the gearing mechanism between the engine and the ignition generator, is adapted to rotate within the hollow portion of the distributor block 1 in such relation that the distributing terminal 90 12, which is connected to the secondary S of the running ignition machine, comes in operative relationship with the row of contacts B; while the distributing terminal 13, which is electrically connected to the 95 secondary s of the starting generator, comes in operative relationship with the row of contacts A. The contacts 14 in rows A and B are preferably serrated while the distributing terminals 12 and 13 are also serrated and pass in close proximity to the contacts 14 without coming in actual engagement therewith. I prefer this jump spark type of construction for certain classes of work as it eliminates the carbon trail where 100 a rubbing contact is used, although it is to be understood that my invention is applicable to distributing mechanism wherein the contacts are of the rubbing type.

The running generator has the usual pri- 110

- mary P and condenser K and circuit breaker C; while the starting generator has primary p , condenser k and circuit breaker c . As shown in Figs. 2 and 3, the secondary s of the starting generator is connected to the distributing terminal 13 through the medium of a terminal 15 and brush 16 carried by the distributor block. When the distributing member 11 is rotated in the direction of the arrow shown in Fig. 2, the individual contacts 14 in row A are cross connected to corresponding contacts in row B, displaced one firing interval from the contact in row A. By this arrangement, it will be seen that when the distributing member 11 is in a position in line with adjacent contacts in rows A and B that the terminal 12 will be in electrical operative position to deliver ignition current to a contact in row A one ignition interval ahead of the contact which is in line with the terminal 13; therefore, it is readily seen that when the terminal 13 is connected electrically to a spark plug in a cylinder in which the piston is on the working stroke that the terminal 12 will be in electrical operative position to deliver current to a spark plug in a cylinder in which the piston is on the compression stroke.
- 30 In certain special cases, depending on the arrangement of the engine cylinders, I may arrange the row of contacts A in somewhat staggered relation with reference to contacts in row B, that is to say, my invention contemplates the relative shifting in angular position of the contacts in row A with reference to those in row B to meet any operative condition necessary, but by way of illustration the contacts in both rows are shown 35 directly adjacent each other. I preferably employ a groove 17 between the two rows of contacts in order to increase the surface therebetween so as to prevent interference between the two sources of ignition current.
- 40 45 It will be understood that various changes may be made in the details of my invention without departing from the spirit of the same and the scope of the appended claims.
- Having now particularly described my invention what I claim is:—
1. In an ignition system for engines using spark plugs for igniting the fuel in its cylinders, an ignition device adapted to produce a spark at any one of said plugs for starting ignition, an independent ignition device adapted to produce a spark at said plug for running ignition, means for electrically connecting the starting ignition device to said plug when the piston in the cylinder containing said plug is in the working stroke and means for electrically connecting the running ignition device to said plug when the said piston is in the compression stroke, said means including a distributor block having two rows of contacts, the contacts of one row being cross connected individually to a corresponding contact one firing interval away in the other row as described.
2. In an ignition system for engines using spark plugs for igniting the fuel in its cylinders, an ignition device adapted to produce a spark at any one of said plugs for starting ignition when the engine is at rest, a second ignition device operatively connected to said engine and adapted to produce a spark at said plug for running ignition when the engine is rotated at sufficiently high speed, and means for electrically connecting said ignition devices alternately to said plug, said means including a distributor block having two rows of contacts, the contacts of one row being cross connected individually to a corresponding contact one firing interval away in the other row as described.
3. In an ignition system for engines using spark plugs for igniting the fuel in its cylinders, an ignition device adapted to produce a spark at any one of said plugs, a second ignition device operatively connected to the engine and adapted to produce a spark at said plug for running ignition when the engine is rotating at sufficiently high speed, means including a distributor block having two rows of contacts, the contacts of one row being cross connected individually to a corresponding contact, one firing interval away in the other row for electrically connecting said ignition devices in succession to said plug and means disconnected from the engine for operating the first mentioned ignition device to produce a spark at said plug for starting ignition when the engine is at rest.
4. In an electrical ignition system for multi-cylinder engines using spark plugs for igniting the charges of fuel in its cylinders, a current supply adapted to produce a spark at said plugs for starting ignition, a second current supply adapted to produce a spark at said plugs for running ignition, a distributor having two rows of electrical contacts, those of one row being individually connected to corresponding contacts one firing interval away in the other row, said connected contact pairs being electrically connected to said plugs according to the firing order of the engine, means for electrically connecting the first mentioned source of current to successive contacts in one row and means for connecting the second mentioned source of current to successive adjacent contacts in the other row.
5. In an electrical ignition system for multi-cylinder engines using spark plugs for igniting the charges of fuel in its cylinders, a current supply adapted to produce a spark at said plugs for starting ignition, a second current supply adapted to produce a

- spark at said plugs for running ignition, a distributor having two rows of electrical contacts with electrical connections from the contacts of one row to said plugs, means for electrically connecting the first mentioned source of current to the contacts in one row, means for connecting the second mentioned source of current to the contacts in the other row and means for cross connecting said contacts whereby the second mentioned source is connected to a plug in advance of the one connected to the first mentioned source in the direction of rotation of the engine.
- 15 6. In an ignition system for engines using spark plugs for igniting the fuel in its cylinders, an ignition device adapted to produce a spark at any one of said plugs, a second ignition device operatively connected to the engine and adapted to produce a spark at said plug for running ignition when the engine is rotating at sufficiently high speed,
- a distributer block having a row of contacts electrically connected to said plugs, a second row of contacts in said block, two distributing terminals operatively connected to the engine to be rotated thereby in coöperation with the contacts in the distributer block, means for connecting the first named ignition device to one of said distributing terminals, means for connecting the second named ignition device to the other of said terminals, means for cross connecting the contacts in the distributer block so that the second named ignition device is connected to a plug in advance of one connected to the first named ignition device and means independent of the engine for operating the first mentioned ignition device to produce a spark at one of said plugs when the engine is at rest.
